UNITED STATES PATENT OFFICE

167,288

STOCKING

Isadore Stillman, Philadelphia, Pa.

Application January 31, 1952, Serial No. 18,314

Term of patent 3½ years

(Cl. D47—7)

To all whom it may concern:

Be it known that I, Isadore Stillman, a citizen of the United States, residing at 6227 N. 12th Street, Philadelphia 41, Pennsylvania, have invented a new, original, and ornamental Design for a Stocking, of which the following is a specification, reference being had to the accompanying drawing, forming part thereof.

I claim:

The ornamental design for a stocking, substantially as shown.

ISADORE STILLMAN.
